DEVICE FOR THE CLEANING OF GROOVED RAILS

Gioachino Benvenuto Isabella, Turin, Italy

Application June 14, 1933, Serial No. 675,843
In Italy July 7, 1932

7 Claims. (Cl. 37—36)

This invention relates to a device for the cleaning of grooved rails.

The cleaning of grooved rails for city trams is ordinarily effected by hand by means of a spade, 5 a narrow end portion of which penetrates into the groove of the rail; the operator works with the spade before him and inclined towards the rail in a manner that the dirt is loosened by the end portion, removed to the outside and thrown 10 out by the spade on both sides of the rail. The use of this tool is very effective but obviously the operation of cleaning the rail is slow and costly. The object of the present invention is a device for attachment to the vehicle running on 15 the rail for the purpose of replacing the hand method of cleaning rails by a mechanical operation which ensures greater speed and economy.

The accompanying drawing shows diagrammatically a construction of the object of the invention.

Figures 1 and 2 show the device in elevation and in plan view, respectively.

Figures 3 and 4 show in detail and on a larger scale the cleaning spade in elevation and plan 25 view, respectively.

A further object of this invention is to avoid any improper working and to provide a cleaning device adapted to be coupled with the lubricating device as disclosed by my United States 30 Patent No. 1,885,726, dated 21st August 1930.

The apparatus according to this invention comprises a rotating shaft 1 parallel to the axles of the wheels, supported from the frame (not shown) and connected to the nearest axle 2 by 35 means of toothed wheels 3 and 4 and a sprocket chain 5. The wheel 3 is keyed on the shaft 1, and the wheel 4 is carried by the movable sleeve 6 of a clutch coupling, the other member 7 of which is keyed on the axle 2. The clutch coupling 40 is operated by means of a known device by the drivers of the vehicle. The shaft 1 transmits motion to the parallel shaft 8 by means of a reducing gearing 9, 10; the shaft 8 carries at each end, above the rails, the friction disc 11 45 against the surfaces of which the driven discs 12 press under the action of springs 13 mounted on bolts 14 which hold together the discs 12, the tension of the springs being adjustable by means of wing nuts.

Each disc 12 carries an arm 15 connected by a helical spring 16 to the rod 17 to the end of which is fixed the cleaning spade, the spring 16 being sufficiently rigid to work as a flexible joint between the arm and the rod.

The rod is urged upwardly by a spring 18 an-

chored to the frame of the vehicle (not shown) in such a manner that the unit 12—15—16—17 formed by the two rail cleaners when stationary forms a beam subject to the action of the two springs 18.

Each rod 17 (Figures 3 and 4) is fashioned at its outer end to a vertical strap 19 holding the spade 20 carried in an inclined position by the swinging member 21 hinged to the rod; the swinging member 21 carrying the spade is under 10 the action of the spring 22 anchored at one end to the said member and at its other end to the rod. The spade works like a scraper in the groove of the rail: It can be extended more or less into the groove by means of the holes 20' and the 15 corresponding pin by which it is fixed to the swinging member 21.

Figure 3 shows the rail cleaner in its working position: A sloping surface 23 of asbestos or other suitable material fixed to an extension 24 of the 20 strap 19, slides on the outer rail head and conveys the dirt raised up by the scraper 20 towards the inside of the track, for which purpose an opening 19' is bored on each portion of the strap 19 for facilitating the passage of the dirt from 25 the outside to the inside of the track.

The working of the device is as follows: normally the beam carrying the scrapers is horizontal. To put it into action the driver of the vehicle has only to connect, by means of a known 30 control, the clutch coupling 6—7 without worrying about the direction of running of the vehicle. The axle 2 then sets in rotation the shaft 1 and this in turn the shaft 8 of the driving friction discs 11.

The driven discs 12 are then urged in the direction of rotation of the discs 11 and against the action of the spring 18 incline the beam thus bringing the rear scraper 20 into operation in the groove of the rail R, (in the direction of 40 running). Any obstruction of the rail due to foreign bodies (for example stones) wedged in the groove momentarily raises the scraper against the action of the spring 22; the fitting of the arm 15—16—17 to the curves, points, etc., is 45 obtained by means of the flexible joint constituted by the spring 16, which works moreover as a shock absorber.

The shaft 8 of the driving discs rotates at a 50 relatively small speed to avoid over-heating of the friction surfaces, which are moreover coated with a suitable material for this purpose.

The shaft 8 may be the driving shaft of a device which delivers grease to the rails, for example of the type described in my United States 55

Patent No. 1,885,726, or of any other device or mechanism.

The details of construction may be varied within wide limits from those described and illustrated without departing from the scope of the invention.

I claim:

1. A device for cleaning grooved rails for use on a tramway or similar vehicle, comprising in combination beams mounted capable of oscillating on the vehicle above each rail, scraper members at the ends of each beam and coupling means between an axle of said vehicle and said beams, by means of which said beams are inclined to one side or the other, respectively, automatically according to the direction of running of the vehicle, in order to bring into operative position one of said scrapers.

2. A device for cleaning grooved rails for use on a tramway or similar vehicle comprising in combination, beams mounted capable of oscillating on the vehicle above each rail, scraper members at the ends of each beam, spring means tending to hold said beams in their inoperative position and means actuated by the vehicle for inclining said beams in one direction or the other, respectively, according to the direction of running of the vehicle, for bringing one or the other scraper respectively into operative position.

3. A device for cleaning grooved rails for use on a tramway or similar vehicle, comprising in combination, beams having flexible arms mounted capable of swinging on the vehicle above each rail, scraper members at the ends of each beam and coupling means between an axle of said vehicle and said beams, by means of which said beams are inclined to one side or the other automatically according to the direction of running of the vehicle, for bringing into the operative position one of the said scrapers.

4. A device for cleaning grooved rails for use on a tramway or similar vehicle comprising in combination a transverse shaft rotatably mounted on the vehicle, beams having flexible arms and loosely mounted on said shaft above each rail, scraper members at the ends of each beam, spring means for holding said beams in the in-

operative position, frictional driving members keyed on said shaft and frictionally cooperating with said beams, and means for transmitting the rotational movement from an axle of said vehicle to said frictional driving members.

5. A device for cleaning grooved rails for use on a tramway or similar vehicle comprising in combination beams having flexible arms mounted capable of swinging on the vehicle above each rail, scraper members mounted capable of swinging at the ends of each beam, spring members for maintaining said scraper members in their operative position, spring means tending to maintain said beams in their position of rest, and means actuated by the vehicle for inclining said beams to one side or the other, respectively, according to the direction of running for bringing one of the said scrapers into operative position.

6. A device for cleaning grooved rails for use on a tramway or similar vehicle, comprising in combination, a transverse shaft rotatably mounted on the vehicle, beams having flexible arms and mounted loosely on said shaft above each rail, scraper members retractably mounted at the ends of each beam, spring members for maintaining said scraper members in their operative position, means tending to maintain said beams in their position of rest, frictional driving members keyed on said shaft and frictionally cooperating with said beams and means for transmitting the rotational movement from one axle of said vehicle to said frictional driving members.

7. A device for cleaning grooved rails for use on a tramway or similar vehicle comprising in combination a transverse shaft rotatably mounted on the vehicle, beams loosely mounted on said shaft above each rail, scraper members at the ends of each beam, spring means for holding said beams in the inoperative position, frictional driving members keyed on said shaft and frictionally cooperating with said beams, and means for transmitting the rotational movement from an axle of said vehicle to said frictional driving members.

GIOACHINO BENVENUTO ISABELLA.
